UNITED STATES PATENT OFFICE.

HYMAN ELIAS COHEN, OF NEW YORK, N. Y., ASSIGNOR TO UNITED STATES HOFFMAN MACHINERY CORPORATION, OF NEW YORK, N. Y., A CORPORATION OF DELAWARE.

PRESSING MACHINE.

Application filed July 24, 1923. Serial No. 653,602.

This invention pertains to improvement in garment presses and the invention has for its object the production of a machine wherein articles and more particularly, knit 5 goods, may be quickly and efficiently pressed.

The main object of the invention is to provide a machine wherein the goods will be automatically fed to and from the pressing elements and likewise to provide means where- 10 by the goods may be subjected to a steaming action and thereafter to the action of a vacuum or suction which tends to dry the goods just as they pass from the press at the dis- charge side or end thereof.

15 The further object of the invention is to provide mechanism whereby the conveyor will be automatically stopped and started and worked in timed relation to the opening and closing mechanism of the press and 20 the steaming and vacuum-producing means likewise brought into operation at given intervals.

With these and other objects in view, reference will be had to the annexed drawings, 25 wherein

Figure 1 is a front elevation of a press and the associated conveying mechanism;

Figure 2 a vertical sectional elevation taken transversely of the press and the con- 30 veyor;

Figure 3 a detail diagrammatic view showing the circuit for controlling the motors which are employed together with means whereby the circuits are established and 35 interrupted;

Figure 4 a detail view showing the parts in a position slightly different from that shown in Figure 3;

Figure 5 a horizontal sectional view taken 40 through the switch box;

Figure 6 a vertical sectional view taken on the line VI—VI of Figure 5;

Figure 7 a similar view taken on the line 45 VII—VII of Figure 5; and

Figure 8 a vertical sectional view of the switch box showing the position of the switch arm when the parts are in the position shown in Figure 4.

The press may be of any approved type 50 and in the instant case is shown as comprising a bed or platen 1 rigidly fixed upon suitable supports 2 which in turn are se- cured to the forward portion of the main frame 3 of the machine. Pivots secured 55 to the upwardly extending elements 4 of the

main frame is a lever 5 which at its forward end has attached to it a pressing head 6, the weight of said pressing head being counter- balanced by a weight 7^a mounted upon the rear end of the lever. Any suitable mecha- 60 nism may be employed for opening and clos- ing the press, that is to say, to secure down- ward and upward movement of the head 6 with reference to the platen 1. To this end I employ a toggle comprising two elements 65 7 and 8, the latter embodying a spring ten- sion device as is common in the art, the lower end of the element 7 being fulcrumed at 9 in the lower rear portion of the frame 3, while the upper end of the element 8 is piv- 70 otally connected to the lever 5 adjacent its rear end. The parts are so proportioned that when the toggle is straightened or brought to the full line position shown in Figure 1, the rear end of the lever will be 75 moved upwardly and the head 6 forced downwardly into contact with the goods to be pressed.

To straighten the pressure applying toggle, 80 (7 and 8) I employ a second toggle comprising the members 10 and 11 pivotally connected at 12. Member 10 at its other end is pivotally attached to a fixed element 13 se- 85 cured in the frame of the machine and the rear end of the element 11 is pivotally at- tached by a bolt 14 to the element 7 of the pressure toggle. A spring 15 tends nor- mally to break the pressure toggle and to thus elevate the head or bring the parts to the dotted line position in Figure 1. 90

The goods to be operated upon are pre- 95 sented to the pressing element by an endless band or belt denoted by 16, which in the present case is shown as passing about and over rollers 17, 18, 19, 20 and 21. Said roll- 100 ers are mounted in a suitable framework de- noted generally by 22 and in the present case shown as formed from angle bars rigidly secured together so as to produce a stable framework which may be moved up to and over the press. The rollers 20 and 21 stand in approximate alinement with the upper face of the bed or platen 1 and the lower run of the belt 16 therefore passes over the buck or bed and in virtual contact therewith. The frame which supports the belt is provided at each side of the bed or platen of the press with table-like or supporting elements 23 and 24 respectively, which underlie the lower run of the belt at such portions and enable the 110

operators to readily place the goods upon the belt at the left of the press and to remove the goods from the belt at the right of the press. While the frame which supports the rollers 5 and belt is shown in the instant case as separate and detached from the press and its frame, it is conceivable that the conveyor belt supporting the frame might be attached to and supported upon the main frame of the 10 press. The independent frame, however, enables me to employ the belt and its supporting frame in conjunction with an ordinary press provided there were no interconnections between the driving mechanism of the 15 press and the means employed for operating a conveyor belt. The axle of roller 21 has secured to it a sprocket pinion or wheel 25 about which passes a sprocket chain 26, said chain also passing about a sprocket wheel 27 20 secured to the shaft of an electric motor 28 shown in the present instance as supported upon a bracket 29 secured to the belt supporting frame 22.

As above noted it is desirable in the handling of knit goods to subject the same to a 25 steaming action and also to the action of a vacuum to dry the same. To this end I employ certain means and mechanism co-related with the operating portions of the press to 30 bring the steaming and vacuum devices into operation at the desired time and in timed relation to the movement of the belt.

The press is designed to be opened and closed through the operation of an electric 35 motor 30, said motor driving a worm 31, which meshes with a worm gear 32, secured to a shaft 33. A pinion 34 is likewise secured to said shaft, said pinion in turn meshing with a gear 35, mounted upon a crank shaft 40 36 supported in suitable bearings 37, secured to the main frame of the press. A pitman 38 is attached to the crank shaft, the upper end of the pitman being pivotally connected to the member 10 of the opening and closing 45 toggle.

It will therefore be seen that rotation of the crank shaft through the operation of the motor 30 and the intermediate gearing will alternately straighten and break the opening 50 and closing toggle and alternately straighten and break the power applying toggle (elements 7 and 8) and cause the press head to be lowered into pressing relation with the platen or buck 1. As a consequence, any 55 material which is upon that portion of the belt 16 which overlies the buck will be subjected to a pressing action.

The head of the press is hollow and provided with a steam chamber 39, steam passing thereto through a pipe 40 as is usual in 60 presses of this type. A normally closed valve 41 opens from the chamber 42 formed by the lower wall of the chamber 39 and a foraminous plate 43 secured to the lower face of the 65 head. If desired, a press cloth may be se-

cured against the exposed face of the foraminous plate. Secured to the valve 41 is a bracket 44, to which is pivotally connected a lever 45, said lever extending rearwardly and being pivotally connected to the upper arm 70 of a link 46, the lower end of which is pivotally connected to the element 11 of the opening and closing toggle.

From an inspection of Figure 2, it will be seen that when the press head is closed that 75 the link 46 is drawn downwardly and rear end of the lever 45 is likewise depressed, said lever contacting the valve stem and depressing the same and permitting steam to pass from the chamber 39 to the chamber 80 42 and through the foraminous plate 43 directly on to the goods supported by the belt. As the head is opened and the parts come to the dotted line position shown in Figure 85 2, it will be seen that the valve stem is permitted to rise and the projection of steam is thus cut off.

The buck is provided with a heating chamber 47 to which live steam passes through a pipe 48, a suitable drain 49 being provided. 90 Live steam passes to the pipe 48 from the supply pipe 50. Overlying the chamber 47 is a secondary or vacuum chamber 51, the upper face of which is formed by a foraminous or perforate plate and pipes 52 and 53 extend from said chamber and are connected into a common exhaust 54. Said exhaust pipe terminates adjacent an ejector nozzle 55 which is in communication with the live steam pipe 48, through a normally closed valve 56, the stem of which projects downwardly and contacts a lever 57 fulcrumed upon a fixed bracket 58. An exhaust pipe 59 extends outwardly from the fitting in which the nozzle 55 is mounted and passes to any suitable point, as a muffler or condenser, as is common. Lever 57 overlies the element 10 of the opening and closing toggle. When said toggle is broken, as seen in dotted lines in Figure 2, element 110 10 contacts lever 57, moves the same upwardly and opens the valve 56, thereby permitting steam to pass through the nozzle 55 and produce a suction in the chamber 51, drawing the air downwardly through the 115 belt 16 and the goods, drying the same.

It will thus be seen that when the press is closed, steam is automatically projected upon the goods; when the press head is open the steam is automatically cut off and the 120 vacuum automatically brought into operation.

In order to effect a proper timing of the motors 28 and 30, I employ suitable switch mechanism, which controls the circuits in 125 which the motors are included. The construction shown is substantially that set forth and claimed in my co-pending application Ser. No. 610,259, filed January 2, 1923.

Secured to the crank shaft 36 is a crank wheel or disk 60 to which is attached a pitman 61, to the upper end of which is connected a rod 62, mounted in suitable guides 63, extending outwardly from the switch box 64. Said rod has secured to it a collar 65, to which is attached at one end a coiled spring 66, the opposite end being secured to the free end of an arm or lever 67, secured 10 to a rocker shaft 68, mounted in suitable bearings in the walls of the switch box.

A rod 69 is mounted in suitable bearings beneath the table of the machine, the outer end of the rod being provided with a handle 15 70. A spring 71 tends normally to draw the rod inwardly and to project its innermost end into the path of the arm 67 and to hold it in one or another position as the case may be (see Figures 3 and 4). When 20 the arm 67 is in the position shown in these two figures, the circuits which lead to both motors are broken. The switch box, on its outer face, carries stops 72 and 73, which serve to limit the upward and downward 25 movement of the arm 67, under the stress of the spring 66. Shaft 68 carries two contact arms 74 and 75 (see Figure 5), arms 74 cooperating with two terminals 76 and 77 (Figure 7), which are connected up with 30 the circuit in which the motor 28 is included. The lines of this circuit are designated generally by 78 and 79. Arm 75 controls the circuit of the motor 30 which operates the press. This circuit is designated generally 35 by 80 and 81 and the terminals therefor are indicated at 82 and 83, and 84 and 85, the arm 75 contacting first with one pair and then with the other pair. The circuit for the motor 30 is closed at every half revolution of the crank shaft 36 and the disk 60, so that it is necessary to employ two sets of contacts for that circuit, whereas, 40 the belt controlling motor is operated only after the press has been closed and then 45 opened.

With the parts shown in the position in Figure 3, at which time the crank shaft 36 is in its lowest position and the press head is closed owing to the straightening of the 50 toggles, the switch arm 67 is held in its neutral position, coming to rest upon the innermost end of the rod 69. As the rod 62 is moved downwardly, during the quarter revolution of the crank shaft, spring 66 is 55 put under tension and when the operator again desires to have the press opened and the belt fed forward, he merely pulls the rod 69 outwardly, thus releasing the arm 67 and permitting the spring 66 to draw said 60 arm downwardly and thereby through the rocking of the shaft 68 brings the contact arms 74 and 75 into bridging relation with the contacts 76 and 77, and 82 and 83, respectively.

65 The motors are then set in operation, the

press head is opened and the belt fed forward. When the crank has made a half revolution, the parts will come to the position shown in Figure 4, and the arm 67 will be drawn upwardly by the spring and 70 both circuits broken. This allows the belt to come to rest with the head of the press in its elevated position. The operator then manipulates the handle 70 and starts the press head downwardly, the arm 75 at such 75 time closing the circuit through the upper terminals 84 and 85, the spring throwing the switch to this position. This closes the head while allowing the belt to remain stationary.

It will thus be seen that the structure is substantially automatic throughout and all that is necessary is for the attendants to see that the goods are properly placed upon the belt and removed therefrom after passing through the press and to pull out the rod 69 when the goods are ready to pass into the press and when they are ready to pass out of the press, after having been operated upon.

While I have described the belt as traveling from the left to the right it is conceivable that the belt may be moved to the opposite direction; this being accomplished by reversing the direction of rotation of the 95 motor 28.

Having thus described my invention, what I claim is:

1. In combination with cooperative pressing elements; an endless belt, one run whereof passes between said elements and to each side of the same; a motor for moving the belt; a second motor for opening and closing the press; switch mechanism operable to close the circuits of the motors in alternation; and means under the control of the operator for arresting the switch mechanism in open position.

2. In combination with cooperative pressing elements; an endless belt, one run whereof passes between said elements; a motor for moving the belt; a second motor for opening and closing the press; switch mechanism for effecting alternate energization of the motors whereby the belt is moved only 110 after a pressing action has been effected; and means under the control of the operator for arresting the switch mechanism in 115 open position.

3. In a press the combination of a buck; 120 a head movable toward and from the same, said head having a perforate under face; means for moving the head toward its open and closed position; means operative through the said opening and closing means 125 to cause ejection of steam through the perforate face of the head when the head is brought to its closed position; a conveyor belt passing between the head and buck; and means for moving the belt step by step. 130

4. In a press the combination of a buck having a perforate pressing face; a head movable toward and from the same, said head having a perforate under face; means for ejecting steam therethrough; means for moving the head into and out of pressing position; vacuum producing means connected to the buck; and means actuated by the opening and closing means for bringing the steam ejecting means into operation as the head is closed and for bringing the vacuum producing means into action when the head is opened.
5. In a press the combination of a buck having a perforate pressing face; a head movable toward and from the same; vacuum producing means connected to the buck; a conveyor cooperative with the buck to present goods to be pressed in position between the buck and the head; means for opening and closing the head; and means actuated by the opening and closing means for bringing the vacuum producing means into action.
6. In a press the combination of a buck having a perforate pressing face; a head movable toward and from the buck and likewise having a perforate pressing face; a toggle mechanism for opening and closing the head; a normally closed steam inlet valve controlling passage of steam to the perforate face of the head; connections between said valve and the toggle mechanism

for opening the valve when the toggle mechanism is in that position to close the head; vacuum producing means connected with the buck; and means actuated by the toggle mechanism when the same is broken to bring the vacuum producing means into operation.

35

7. In a press the combination of a buck; a head; toggle mechanism for opening and closing the head; a crank shaft; an electric motor for actuating the same; connections between said crank shaft and the toggle mechanism for actuating the latter; a conveyor adapted to be moved over the buck; a motor for actuating said conveyor; and switch mechanism controlled by the crank shaft for opening and closing the circuits leading to the motors.

40

8. In a press the combination of a buck; a head; toggle mechanism for opening and closing the head; a crank shaft; an electric motor for actuating the same; connections between said crank shaft and the toggle mechanism for actuating the latter; a conveyor adapted to be moved over the buck; a motor for actuating said conveyor; switch mechanism controlled by the crank shaft for opening and closing the circuits leading to the motors; and means under the control of the operator for arresting the switch mechanism in open position.

45

In testimony whereof I have signed my name to this specification.

HYMAN ELIAS COHEN.
